UNITED STATES PATENT OFFICE.

ALEX A. CLARKE, OF DALLAS, TEXAS.

SURFACE-TREATING MACHINE.

1,356,339.

Specification of Letters Patent. Patented Oct. 19, 1920.

Application filed April 26, 1919. Serial No. 292,992.

To all whom it may concern:

Be it known that I, ALEX A. CLARKE, a citizen of the United States, residing at Dallas, in the county of Dallas and State of Texas, have invented certain new and useful Improvements in Surface-Treating Machines, of which the following is a specification.

This invention relates to new and useful improvements in surface treating machines.

The purpose of the invention is to provide a machine in which the surface treating member is driven by intermediate means from a motor displaced from the member, together with means for effecting adjustments of the surface treating member with relation to the work.

In carrying out the invention a supporting frame is adjustably mounted on shoes or runners. Suitable means as handles may be provided on the frame manipulating the same. A surface treating member is mounted in the frame and may assume the form of a sleeve fitting on a drum. A motor is mounted in the frame and a train of gears driven by the motor operates the member. By adjusting the frame the member is raised and lowered and such means is employed.

The invention will be more readily understood from a reading of the following specification and by reference to the accompanying drawings, in which an example of the invention is shown and wherein:

Fig. 1 is a side elevation of a machine embodying the invention,

Fig. 2 is a partial plan view of the same,

Fig. 3 is a detail of the runner and cross bar connection,

Fig. 4 is a side elevation of a modification,

Fig. 5 is a side elevation of still another form,

Fig. 6 is a vertical sectional view on the line 6—6 of Fig. 5, and

Fig. 7 is a partial plan view of the machine shown in Fig. 5.

In the drawings the numeral 1 designates a frame which is composed of side plates 2 connecting end members 3. The side plates are fastened to the end members by screws 4. The end members having vertical columns 5 at each side in which posts 6 are mounted. Each post has its lower end reduced and fastened in a cross bar 7 as is shown in Fig. 3. The cross bars project

beyond the posts and have reduced ends 8 fitting runners 9 and fastened therein by set screws 10. The runners extend longitudinally of the machine and have their projecting ends turned up so as to avoid scratching the surface being worked on.

At the top of each column a boss 11 is provided and a small sprocket wheel 12 screwthreaded on the post is mounted on each one. Keepers 13 fastened on the end members confine the sprocket wheels 12 and support the frame. The posts are not threaded in the columns and thus by rotating the wheels 12 the latter are elevated or lowered on the posts, thereby elevating or lowering the frame. An endless sprocket chain 14 extends around the machine and engages the wheels 12. This chain passes around an idler sprocket wheel 15 at one end and is driven by a sprocket wheel 16 at the other end. The wheel 16 is fastened on a shaft 17 rotated by a handle 18 which with a companion handle 18' at the other end is mounted between brackets 19. The wheels 15 and 16 are supported on the upper brackets. These brackets extend from and form parts of the end members 3. By rotating the handle 18 the chain is traversed and the wheels 12 simultaneously rotated thus evenly adjusting the frame and maintaining its level.

The columns 5 have ears 20 set back from their sides and these receive plates 21 which are fastened thereto. The plates 2 are spaced from the inner plates 21. The plates 21 have their lower edges some distance above the lower edges of the plates 2 and are arched above drums 22 and 24. The drum 22 has trunnions 23 engaging in the side plates 2, while the drum 24 also has trunnions 25 engaging in said plates. By removing the rear side plate 2 (Fig. 1) the drums may be removed. A sleeve 22' is fitted on the drum 22 and a sleeve 24' is fitted on the drum 24. The sleeve 22' may be of coarse abrading material and the sleeve 24' of fine abrading material so that when the machine is moved to the left (Fig. 1) the coarse abrading member will first attack the work followed by the fine abrading member. The sleeves may be of polishing or buffing materials if desired.

In the space between the plate 2 and plate 21 at the front side (Fig. 1) of the machine gears are disposed. Gears 26 are fastened on the trunnions 23 and 25

and each meshes with a gear 27. The gears 27 are driven by a common driving pinion 28 fastened on a motor shaft 29. A motor 30 is mounted between the plates 21 on brackets 31. The sizes and relations of the gears may be changed if desired to obtain various speed ratios.

By supplying current to the motor the drums are revolved. The operator moves 10 the machine over the work and the surface is removed, polished or treated according to the nature of the sleeves used. The drums are readily adjusted by turning the handle 18.

15 In Fig. 4 I have shown a modified form substantially the same as the machine just described except that only a single drum 40 is employed. This drum has a surface treating sleeve 40' and trunnions 41. A gear 42 is fastened on one of the trunnions and is driven by a gear 43 which meshes with the pinion 28 of the motor shaft 29. The motor 30 is mounted nearer one end of the frame and the machine is shortened.

25 In Figs. 5 to 7 inclusive I have shown another form in which the invention may be employed. In this instance the runners 9 cross bars 7, posts 6 sprocket wheels 12, and keepers 13 are used. An end member 50 and 30 a shorter end member 51 are used. The end member 50 has vertical columns 52 at each side receiving the posts at one end of the frame. Ears 53 cast on the columns are set back from the outer sides of the same. 35 Ears 54 are provided on the end member 51. Side plates 55 connect the end members and are fastened to the ears 53 and 54. Lugs 56 are provided on the side plates and receive the other pair of posts.

40 The end members have outwardly extending brackets 57. A handle 58' is fixed between the brackets of the member 51; while a handle 58 is rotatable between the brackets of the member 50. The handle 58 has a 45 shaft 59 extending above its top bracket with a sprocket wheel 60 fixed on said shaft. An endless sprocket chain 61 passes around the sprockets 12 and 60 and by turning the handle 58 the chain is traversed as in the 50 other forms, thus adjusting the frame.

The end members have ears 63 spaced inwardly from the ears 53 and 54 and inner plates 62 extending between the end members are fastened to the ears 63. Below the 55 inner plates a cross bar 64 fastened to the side plates braces the same. The side plates are cut back at their lower left-hand (Fig.

5) corners and provided with collars 65 receiving the shaft 66 of a drum 67 having a surface treating sleeve 67'. The purpose 60 of this arrangement is to dispose the drum at one end of the frame and to one side of the adjustable supports. It will be seen that if the handle 58' and its brackets 57 were omitted the drum would extend beyond the end 65 of the frame. A gear 68 is fastened on the drum shaft 66 and is driven by a gear 69 mounted between the plates 55 and 62 thereabove. The gear 69 meshes with a pinion 70 mounted on a motor shaft 71 of a motor 72. The motor 72 is mounted on brackets 73. The operation is the same as in the other forms.

What I claim, is:

1. In a machine of the character described, a supporting frame, upstanding apertured members secured to the supporting frame, approximately vertical posts longitudinally movably mounted within the apertured members and having their upper portions screw-threaded, said posts extending below the supporting frame and adapted to support the same, sprocket wheels having screw-threaded engagement with the screw-threaded portions of the posts, means to prevent the sprocket wheels moving vertically with relation to the supporting frame, a sprocket chain connecting the sprocket wheels, a sprocket wheel engaging the sprocket chain, means to turn the last named sprocket wheel, a surface treating member 90 connected with the supporting frame, a motor carried by the supporting frame, and gears connecting the motor and the surface treating member.

2. In a machine of the character described, an outer supporting frame embodying a removable side, an inner frame secured to the outer frame and having a side spaced from the removable side, a rotatable surface treating member detachably connected with the sides of the outer frame, a gear permanently secured to one end of the rotatable member and arranged between the spaced sides of the inner and outer frames, a motor arranged within and secured to the inner frame, gearing connecting the motor and the first named gear and arranged between the spaced sides, a support connected with the outer frame, and means to vertically adjust the outer frame with relation 100 to the support.

In testimony whereof I affix my signature.
ALEX A. CLARKE.
